UNITED STATES PATENT OFFICE.

JOHN NELSON, OF CHICAGO, ILLINOIS, ASSIGNOR TO ILLINOIS MALLEABLE IRON COMPANY, OF CHICAGO, ILLINOIS, A CORPORATION OF ILLINOIS.

CISTERNS.

SPECIFICATION forming part of Letters Patent No. 737,859, dated September 1, 1903.

Application filed March 1, 1901. Serial No. 49,527. (No model.)

To all whom it may concern:

Be it known that I, JOHN NELSON, a citizen of the United States of America, residing at Chicago, in the county of Cook, in the State 5 of Illinois, have invented certain new and useful Improvements in Cisterns, of which the following is a specification.

My invention relates to cisterns for water-closets and the like, but more particularly to 10 the valve mechanism for effecting a discharge of water from the cistern for the purpose of flushing the bowl; and its object is to provide simple, efficient, and reliable valve mechanism of that type known as "seat-operated 15 valves" in which the valve mechanism is automatically operated by the seat of the water-closet.

In the drawings, Figure 1 is a section of the cistern, taken on line A B of Fig. 2, the water-closet bowl and connection being shown 20 in elevation; Fig. 2, an elevation of the parts within the cistern, the front side of such cistern being removed; Fig. 3, a plan view of the cistern; Fig. 4, an elevation of the valve 25 and parts immediately coöperating therewith and showing the catch in set position ready to open the valve as soon as permitted by the seat; and Fig. 5 an elevation of the valve, showing the same as opened by the catch device 30 and during the period of discharge of water from the cistern.

The cistern 1, which may be either of the low-down type, as herein shown, or of the high-up type, has a bottom opening through 35 which extends a nozzle 2, secured therein by the usual couplings, and having at its upper end a valve-seat 3, on which seats the valve 4. This valve preferably has at its periphery a seat proper of rubber or other suitable 40 material. Two arms or standards 5 rise from this nozzle and are connected together at their top by a cross-bar 6, having a central hole 7 to receive and guide a sleeve or plunger 8. The valve has a stem 9, received by the bore 45 of the sleeve, and thereby also guided, and, further, has a truncated conical portion or enlargement 10, forming a shoulder 11 for the catch. As shown, this enlargement and stem are preferably integral with the valve-body 50 itself. The valve-stem is preferably flattened on one or more sides to permit the air within

the sleeve to escape when such sleeve is depressed.

The catch mechanism herein illustrated is an example of what may be employed for the 55 purpose desired, and the same comprises a ring 12, having a screw-threaded socket-piece 13 at one side to receive the stem 14 of a ball-float 15, which is normally submerged. At the side opposite the socket-piece the ring has 60 a hook 16, pivoted at the end of lateral lugs 17 at the lower end of the sleeve and having a curved lower end 18, adapted to engage the shoulder 11 under certain conditions, as hereinafter set forth. The valve may have a de- 65 pending stem guided by a suitable guide 19, arranged in the nozzle. (See Fig. 1.)

To operate the valve mechanism and the catch by means of the seat of the water-closet, the following instrumentalities may be employed as being suitable and preferable for this purpose: A rod 20 is screwed into or otherwise secured to the sleeve 8 and is pivotally connected at its upper end to the end of a lever 21, which is pivoted to a fulcrum-rod 22. 70 The other end of this lever has pivotally connected to it the lower end of a vertical rod 23, whose upper end is in connection with a vertical operating-rod 24. This rod 24 works in a barrel 25 or cylinder, which extends through 75 the bottom of the cistern and contains a spiral spring 26, bearing against an adjusting-nut 27, screwing on the lower end of such rod 24. A cap or thimble 28 screws on the end of the rod 24 and receives the thrust of the seat 80 mechanism, as hereinafter described. The barrel or cylinder 25 also forms a support for the fulcrum-rod 22, which is attached thereto by a collar 29.

The nozzle 2 from the cistern connects with 90 the water-discharge pipe 30, communicating with any suitable bowl 31 of a water-closet and having a seat 32 normally held in slightly-raised position, as shown in Fig. 1, by means of the downward pressure of the rod 24 on the 95 end of a lever 33, secured to the seat and extending beyond the pivot thereof. The ball-cock 34 and the after-fill pipe 35, emptying into the overflow-pipe 36, being so well known do not require any detailed description.

Assuming that the cistern is filled with water to the normal level and the parts are in

their normal position, as shown in Fig. 2, the operation is as follows: When the seat is depressed by occupation thereof, the rod 24 is forced upward against the tension of its spring 5 by reason of the upward thrust of the seat-lever, and the movement is communicated through the rods and levers described, so that the sleeve 8 will be depressed, such sleeve sliding upon the stem 9. The pivotal point of the 10 catch device will consequently be depressed or carried downward, and when the sleeve is depressed to its limit the hooked end 18 will engage under the shoulder 11, inasmuch as the buoyant effect of the small float 15 is to bring such end toward the central axis of the 15 valve. The catch remains thus in engagement with the valve so long as the sleeve is in depressed position—that is, so long as the seat is occupied. When, however, the seat 20 is now vacated, the tension of the spring 26 will restore the parts to normal position, thereby raising the sleeve and also opening the valve, because such valve and sleeve are connected together by the catch. The cistern 25 will now be drained of water for flushing the bowl, and the discharge-valve will remain in its raised or open position until the water in the cistern has so far receded as to carry the small float 15 downward with it, 30 thereby releasing the hook or catch from the shoulder 11 and permitting the valve to close by gravity. The tank will thereupon be filled with water by the ball-cock in the usual manner, and the cistern will be ready for the next 35 operation.

It is evident from the foregoing description that the catch mechanism is set or put into engagement with the valve at the moment when the seat is occupied and that the 40 restoration of the parts to normal position when the seat is vacated causes the catch mechanism to elevate and open the valve, which is thereafter released and permitted to close at the proper time—that is, when 45 the water has been substantially drained from the cistern. While I have herein shown my invention as applied to a cistern of the low-down type, yet it is obvious that the same is applicable to the high-up or over- 50 head type, the only changes being the lengthening of the discharge-pipe 30 and of the rod 24, rendered necessary by the elevation of the valve mechanism. Furthermore, while I prefer to use a spring for the purpose of 55 applying tension on the rod 24, yet it is evident that its equivalent, a weight, might be substituted. The spring, however, is preferred, particularly because of compactness and capability of adjustment in tension.

60 The construction and operation of my device is such that in case the weight of the occupant is momentarily withdrawn, either purposely or accidentally, so as to open the valve, a partial flush will occur, inasmuch as the valve 65 after being thus opened will be closed again immediately upon the reoccupation of the seat. It is apparent, therefore, that when

the valve is opened it will stay open and drain the cistern only in case the bowl-seat remains in its normal partially-raised position, and that consequently the valve is to this extent controlled by the occupant. 70

I claim—

1. In a tank or cistern for water-closets and the like, the combination, with the tank, of a 75 discharge-valve therein, a vertically-movable and normally upwardly-pressed catch arranged in the tank and when depressed adapted to engage the valve while closed but not to open the same at that time, seat-controlled 80 mechanism coöperating with said catch to depress it when the seat is occupied and to permit the catch to rise and the engaged valve to open when the seat becomes unoccupied, a submersible float at all times connected 85 with said catch and arranged to positively move the same laterally of the valve, both into and out of engagement with such valve, and suitable water-supply mechanism separate and independent, both in structure and 90 operation, from said float.

2. In a tank or cistern for water-closets and the like, the combination, with the tank, of a discharge-valve located at the bottom of the tank and provided with a vertical stem, a 95 normally upwardly-pressed and vertically-movable catch device comprising a sleeve or plunger 8 movable vertically and axially upon the valve-stem and guided thereby, and a depending pivoted hook arranged to engage the 100 valve while closed but without effecting the opening thereof at such time, seat-controlled 105 mechanism coöperating with said catch device to depress the same when the seat is occupied, to permit the hook to engage the valve 110 and, when the seat becomes unoccupied, to permit the catch device to rise and open the engaged valve, a submersible float connected directly to said hook for swinging the latter both into and out of engagement with the 115 valve, and suitable water-supply mechanism automatically controlled by a float which is separate and independent of the first-named float.

3. In a tank or cistern for water-closets and the like, the combination of a vertically-movable discharge-valve of the pull type which is arranged near the bottom of the tank and is provided with a rigid vertical stem having a circumferential shoulder, a vertically-movable 120 catch also arranged near the bottom of the tank and adjacent the valve, means actuated by the closet-seat for depressing the catch, a float connected directly to the catch and adapted to actuate it positively both toward and away from the valve-stem to permit engagement and disengagement of such catch and said shoulder, suitable water-inlet mechanism for said tank and a second float adapted to control said mechanism and arranged to operate independently of the first float and its catch. 125

4. In a tank or cistern for water-closets and the like, the combination with a water-closet,

- its movable seat and the tank and the water connections, of a discharge-valve of the pull type and adapted to be moved vertically, a rigid stem projecting vertically upward from 5 said valve, a catch device pivoted near the bottom of the tank adjacent the valve and adapted to engage and lift such valve, a vertically-movable sleeve telescoping with the stem and connected at its lower end to said 10 catch device and adapted to put such device into engagement with the valve, and tension-provided seat-controlled mechanism connected to and reciprocating such sleeve.
5. In a cistern, the combination, with a cistern 15 and its discharge-valve of the pull type having a rigid stem, of a reciprocating sleeve, movable axially of such stem and provided with a bore to receive the upper end of such stem, said sleeve and stem telescoping, a catch 20 device pivoted to the sleeve at one side of the stem and adapted to engage the valve when the sleeve is depressed.
6. In a cistern, the combination with the cistern and its discharge-valve having a rigid 25 vertical stem 9, a vertically - reciprocating sleeve 8 provided with a bore to receive such stem and having a lateral lug 17 at its lower end, said sleeve and stem telescoping, a catch device having a hook portion 16 pivoted at its 30 upper end to said lug and adapted to engage the valve with its other end, and a float operatively connected to said hook portion.
7. In an automatic water-closet, a cistern 35 having water - supply mechanism, its discharge-valve having a rigid vertical stem 9 a sleeve 8 provided with a closed bore in which such stem slides and telescopes and having a lateral lug 17 at its lower end, a catch device having a downwardly-extending hook portion 40 16 pivoted at its upper end to said lug and adapted to engage the valve with its other end when the sleeve is depressed, a float independent of the water-supply mechanism for operating the catch device, in combination with the 45 bowl, its removable seat having a lever, water connections between the cistern and bowl, a spring-pressed rod 24 movable against its tension by the said seat-lever when the seat is occupied and a connection between said rod and the sleeve to set the catch device in engagement with the valve to open it when the rod is relieved by the vacating of the seats. 50
8. In an automatic water-closet, a cistern, its discharge-valve, a reciprocating sleeve 8, catch mechanism carried by the sleeve at its 55 lower end and adapted to be put into engagement with the valve when the sleeve is depressed, in combination with the bowl, its movable seat provided with a lever, a spring-pressed rod 24 adapted to be moved against 60 its tension by the seat-lever, and a lever 21 pivoted in the cistern and having one arm in connection with the rod 24 and its other arm with the sleeve.
9. The combination with a tank 1 having a 65 discharge-passage 2, a valve 4 adapted to govern said passage and provided with a stem 9, standards 5 having a cross-bar 6 arranged in the tank above the valve, said cross-bar having a central guiding-opening 7, a sleeve 8 70 passing through said opening and receiving the upper end of the valve-stem, a catch 16 pivoted to the lower end of the sleeve at a point below said cross-bar and adapted to engage the valve-stem, and suitable water-inlet 75 mechanism.
10. The combination, with a tank or cistern, of a discharge-valve having a stem, a reciprocating sleeve, movable axially of such stem and provided with a bore to receive the 80 upper end of such stem, means for preventing the trapping of air in such bore, and a catch device arranged on the sleeve to engage the valve-stem when such sleeve is depressed. 85
11. The combination, with a tank or cistern, of a discharge-valve having a stem, a reciprocating sleeve, movable axially of such stem and provided with a bore to receive the upper end of such stem, said stem being flattened to prevent trapping of air in said bore, and a catch device arranged on the sleeve to engage the valve-stem when such sleeve is depressed. 90
